UNITED STATES PATENT OFFICE

CHARLES P. EISENHAUER, OF DAYTON, OHIO, ASSIGNOR TO THE DURO COMPANY, OF DAYTON, OHIO, A CORPORATION OF OHIO

COMPRESSOR

Application filed August 15, 1927. Serial No. 212,886.

My invention relates to a compressor and means of circulating gas or fluid.

It is the object of my invention to provide means of circulating gases or fluids through a series of reciprocating pistons actuated by a continuously rotating driving member.

It is a further object of my invention to provide such means in combination with a direct electric drive and in combination with means for cooling the gas or fluid so handled.

It is a further object to provide a single unitary construction within a single housing, mounted on a single foundation from which the motor fluid or gas actuating units may readily be detached when the unitary cover is removed.

Referring to the drawings:

Figure 1 is a section through a part of the motor, the circulating pipes, gas or fluid circulating mechanism and the housing on the line 1—1 of Figure 2;

Figure 2 is an end elevation from the circulating end of the complete apparatus;

Figure 3 is an enlarged section of the gas or fluid circulating mechanism on the line 3—3 of Figure 2;

Figure 4 is a section on the line 4—4 of Figure 3;

Figure 5 is a section on the line 5—5 of Figure 1 looking in the direction of the pistons.

Referring to the drawings in detail, 1 is the foundation for the complete apparatus, which foundation or platform has a marginal upstanding flange or rib 2. On the floor of this foundation 1 are a pair of spaced supporting arms 3 arranged in pairs at either end of the platform or base and having on their upper ends the fore and aft supporting rails 4, the ends of which are mounted upon the respective supports 3 on either end of either side of the platform 1. Upon these supporting rails 4 is mounted the electric motor 5 and the housing of the compressor 6. Thus, these two units can be detached and moved therefrom when desired, but, when they are in position, they are maintained in a predetermined position with respect to the cover 6' and a plurality of circulating coils 7 which surround them. As the electric motor and the compressor are directly connected, these support-

ing rails, upon the common base, provide for perfect alignment of the several parts. The cover 6' is mounted on the base and provided with louvers 8 at either end thereof so that air may be circulated over the motor 5 and compressor 6 by the fan mounted on the armature shaft 10 of the electric motor. The pipes 7 are spaced from one another by the spacer bars 11.

This armature shaft 10 carries on its outer end a driving screw consisting of a sleeve 12 and a screw 13. This screw is adapted to turn within a slot in insert 14 in the cylindrical piston 15 and is yieldingly held in such a position by the cylindrical plunger 16 working within that piston and impelled against the screw by the internally-located helical spring 17, one end of which abuts against the bottom of the cup-shaped plunger 16 and the other against the externally-threaded end plate 18 of the piston 15.

The turn of the screw 13 reciprocates the piston 15 within the cylinder 19, of which pistons there are a plurality arranged about the circumference of the cylinder block 20 near the periphery thereof. As the screw turns, these pistons are reciprocated one by one so that a continuous flow of gas or fluid will be caused.

The piston 15 carries at its end opposite to the screw end a spider 21 between the arms of which are the ports 22 which are adapted to be sealed by the valve plate 23, the reciprocation of which is limited by the screw head 24 carried in the spider at 25, which head is spaced from the spider a distance sufficient for the plate 23 to move backwardly and forwardly, such plate being journaled or supported upon the shaft of the screw, as at 26. The slots 14a in the insert 14 act as inlet ports to the interior of the pistons 15. The air or gas or fluid passing into the cylinder 19 when the piston is withdrawn will pass through the ports 22 beneath the plate 23 into the compression passageways 27, within a cylinder member 28 in the center of which is carried a second screw 29 having a spaced head 30 and a valve plate 31 mounted thereon adapted to close the passageways 27. This valve plate is yieldingly maintained in closed position by a

helical spring 32, one end of which engages said plate 31 and the other end seated against the interior wall of the chamber 33 of the cylinder head 34. Thus, on the return stroke of the piston 15 the gas or fluid contained within the cylinder 19 is compressed by the piston which is sealed therefrom by the plate 23, lifting the plate 31 against the spring 32 and forcing the fluid or gas into the chamber 33 and through the passageway 34^a into the distribution head 35 where it opens the ball valve 50 and passes into the port 51 and thence to the inner series of coils 7, then to the outer series of coils 7, as shown at 7^a, and thence through a pipe 37 to the source of supply.

From the source of supply the gas is delivered to the distribution head 35 through a pipe 36. The gas thus delivered to the head opens a ball valve 48 and then passes into a pipe 49 by which it is delivered to a chamber 38. This chamber is formed by the housing 39 which is an integral part of the cylinder block 20 in which are located the cylinders 19. This cylinder block is provided with a plurality of ribs 40 for radiating heat. The bottom of the chamber 38 is filled with lubricant 41 through the filler opening 42, which lubricant is supplied by the wick 43 through the supply means 44 to the worm 13.

It will be noted that I have thus provided a direct electric motor drive and have translated the high speed of that motor into the relative slow speed reciprocating pistons of which one at least is always in operation so that there will be an even and continuous positive flow of gas or fluid through the system. By having a common motor frame 45 to which is bolted by the bolts 46 the casting 39 and the cylinder block 20 with the cylinder head 34, I am able to provide a fully aligned apparatus. The gas-tight bearing mechanism is carried in the end of the cage of the motor and the cages are connected together by the bolts 47.

It will be understood that I desire to comprehend within my invention such modifications as may be necessary to adapt it to varying conditions and uses.

By screw or worm I mean placing a half of a right hand screw and a half of a left hand screw together so that the ends meet.

The circuit of the gas is as follows: Gas or fluid enters through the pipe 36 from the source of supply into the distributor head 35, unseating the ball valve 48 and then passes through the pipe 49 which leads to the chamber 38, Fig. 3. From the chamber 38 the gas passes around the sleeve 12 and screw 13 through one of the openings 14^a into a piston 15, thence through the ports 22 into the cylinder, the return stroke of the piston compressing the gas in the cylinder and opening the valve 31, thereby allowing the gas to pass from the cylinder head into a port 34^a

and thence to the distributor head. The gas thus returned to the distributor head then passes through the port 51 into the coils 7 and after circulating through said coils is returned to the source of supply by the pipe 37.

Having thus fully described my invention, what I claim as new and desire to secure by Letters Patent, is:—

1. In combination, a common base, a plurality of standards, supporting rails supported thereby, a motor and compressor resting thereon, a plurality of cooling pipes wound around said motor and compressor, passing above said base and beneath said supporting rails and spaced from said motor and compressor, and a fan carried by said motor.

2. In combination, a common base, a plurality of standards, supporting rails supported thereby, a motor and compressor resting thereon, a plurality of cooling pipes wound around said motor and compressor, passing above said base and beneath said supporting rails and spaced from said motor and compressor, and a fan carried by said motor, and a case mounted on said common base having louvers at either end for the circulation of air therethrough.

3. In a compressor, a base, a plurality of standards supported thereby, supporting rails on said standard, a motor and a compressor on said rails in operative alignment with each other, and a plurality of cooling pipes wound around said motor and compressor and passing above said base and beneath said rails and spaced from said motor and compressor.

In testimony whereof, I affix my signature.

CHARLES P. EISENHAUER.
